UNITED STATES PATENT OFFICE.

CHARLES S. SALFELD, OF MILWAUKEE, WISCONSIN.

INTERNAL-COMBUSTION MOTOR.

1,262,850.

Specification of Letters Patent. Patented Apr. 16, 1918.

Application filed March 23, 1914. Serial No. 826,472.

To all whom it may concern:

Be it known that I, CHARLES S. SALFELD, a citizen of Germany, residing at Milwaukee, county of Milwaukee, and State of Wisconsin, have invented new and useful Improvements in Internal-Combustion Motors, of which the following is a specification.

My invention relates to that class of internal combustion engines, in which a preliminary compression of the air charge is secured preparatory to its delivery to the combustion chamber.

The primary object of my invention is to provide for an automatic pressure control of the delivery of compressed air to the cylinder, whereby the construction is not only simplified, but the air admission timed in correspondence with conditions in the cylinder, instead of providing for the operation of mechanically opened admission valves at fixed intervals regardless of cylinder conditions.

A further object of my invention is to improve the valve structures with a view to securing greater efficiency and economy in operation.

In the drawings—

Figure 1 is a sectional view of an internal combustion motor embodying my invention, drawn to a plane common to the axis of the cylinder, and of the air inlet and exhaust ducts.

Fig. 2 is a similar view illustrating my invention in modified form.

Fig. 3 is a detail sectional view of a valve actuating device adapted to be used, either with the motor shown in Fig. 1, or with that shown in Fig. 2 for utilizing differences in pressure to operate a controlling valve.

Fig. 4 is a detail sectional view of a modified form of construction adapted to be substituted for the device shown in Fig. 3.

Like parts are identified by the same reference characters throughout the several views.

1 is a cylinder of a two cycle internal combustion motor and 2 is a piston, the motion of which is transmitted in the usual manner to the crank 3 through a connecting rod 4. The piston 2 is of the ordinary cup shaped type, except that at its outer end it carries a larger piston 5, the latter serving to compress air on the return stroke in the annular

chamber 6. During the expansion stroke of the piston 2, air is drawn into the cavity 6 through a duct 7, the inner end of which is provided with a check valve 8. Air passing this check valve is received in a chamber 9 formed in or upon the outer wall of the cylinder and from which it passes through a port 10 to the chamber 6 between the inner and outer cylinder walls.

During the compression stroke, the check valve 8 will of course be closed, a spring 12 being preferably employed to insure the initial closing of this valve. The compressed air will be expelled from chamber 6 (when the pressure becomes sufficient), through a port 14, which is normally closed by a spring actuated check valve 15. This compressed air is received in a reservoir or air chamber 16, where it is stored for use in scavenging and charging cylinder 1. During the completion of the expansion stroke and the initial period of the compression stroke, air will be delivered from chamber 16 to the cylinder 1 through a duct 18 and the inlet port 19 of said cylinder. A check valve is employed to prevent an out-flow of burnt gases from cylinder 1 into the duct 18 during the expansion stroke. In Fig. 1 this valve is illustrated as a check valve 20 composed of a flap of flexible material, having sufficient resilience to initially close from open position when the pressure in cylinder 1 and duct 18 are equalized. In Fig. 2 delivery through the inlet port of cylinder 1 is controlled by a rotary valve presently to be described. But in either case it will be understood that the valve opens automatically for delivery of air and closes when the pressure in the cylinder 1 exceeds that in duct 18 during the expansion stroke. Cylinder 1 exhausts at the completion of the expansion stroke through a port 22 into cavity 23 with which exhaust duct 24 communicates. Ducts 26 and 27 pertain to the circulatory system connected with the water jacket cavities 28.

It will be observed that the port 19 is longer than the port 22, both ports, however, being so located that they will each be fully open when the piston 2 completes the expansion stroke. Port 19 will therefore be partially opened before the piston uncovers any portion of port 22. But during the expansion stroke, valve 20 will of course be held

closed under the pressure of the expanding gases in cylinder 1 until the exhaust port 22 is uncovered, thus preventing the burned gases from entering the duct 18. As soon as port 22 is uncovered, such gases will be delivered into the exhaust duct 24, thus relieving the pressure in the combustion chamber, whereupon the pressure of air in duct 18 will open valve 20 and fresh air will rush in to 10 scavenge the cylinder. The initial compression movement of piston 2 will then first close the exhaust port 22, while port 19 is still partially open. At this moment, the combustion chamber will be filled with fresh 15 air at a pressure somewhat in excess of atmospheric pressure but less than the full pressure of the air in chamber 16. But port 19 is elongated sufficiently to permit the pressure to substantially equalize on opposite 20 sides of valve 20 before the piston closes port 19, and the cylinder, or the combustion chamber thereof, is therefore charged with air at substantially the full pressure of the air in chamber 16. The means for carbureting 25 the air is not material, as this forms no part of the invention herein claimed. Hydro-carbon fuel may be delivered through an injector 17.

Briefly reviewing the operation of the construction illustrated in Fig. 1, it will be understood that the outward movement of the piston constitutes the suction stroke for chamber 6 and the expansion stroke for the combustion chamber. The inward stroke of 30 the piston constitutes the compression stroke for both chambers. During the outward or suction stroke for chamber 6, inlet valve 8 will be opened, air being admitted more or less freely to chamber 6 in accordance with 35 the position of the throttle valve 30 in duct 7. During this stroke, check valves 15 and 20 will both be closed, since the pressure in chamber 16 is then greater than in chamber 6 where a partial vacuum is being formed, 40 and the pressure in the combustion chamber is greater than that in duct 18 owing to the expansion of the gases in the combustion chamber during combustion. At the completion of this stroke, valve 8 will be closed by 45 spring 12 as soon as the pressure in chamber 6 is substantially equal to the atmospheric pressure, and during the compression stroke, valve 15 will open as soon as the pressure in chamber 6 exceeds that in chamber 16. 50 Valve 20, as previously explained, is forced open by the pressure in chamber 16 and duct 18 as soon as the expanding gases are permitted to exhaust through exhaust port 22.

Modified structure of Fig. 2.

60 In Fig. 2 the air inlet ports 10^a are uncovered only when the piston 5 is substantially at the outer limit of its stroke. A port 14^a is provided for delivery of air from

chamber 6 into the storage or compressed air 65 chamber 16. This port is normally closed by a spring actuated valve 15 like that shown in Fig. 1. But it will be observed that the port 14^a is so located that on the compression stroke, piston 5 will close this port during 70 the initial compressing movement, after which continued compression in chamber 6 is utilized to force air through a port 35 and past a spring actuated check valve 36 into a duct 37, leading to valve chamber 38, from 75 which this air may be delivered to the cylinder through a port 39. Air from chamber 16 may also pass to valve chamber 38 through a duct 18^a, similar to the duct 18 shown in Fig. 1, but which in this case need 80 not be as large as said duct 18. The air delivered through the duct 18^a may pass to the combustion chamber through a port 19^a, provided for that purpose. But this only occurs when piston 2 is substantially at the 85 outer limit of its stroke with said port 19^a uncovered. A rotary valve 42 controls the delivery of air through duct 37. This valve is adapted in one position of adjustment to 90 cut off delivery to the valve chamber 38 through port 47 and simultaneously permit a delivery of such air through port 43 into a duct 44 which may convey it to another reservoir 41. A valve 45 is located in the cavity 38, said cavity being cylindrical. Valve 45 95 is of the Corliss type adapted to be adjusted to cut off air admission from duct 37 through port 47, and also to cut off air delivery through port 39. The valve 45 divides chamber 38 into two compartments, one for the 100 supercharging air and the other for the scavenging air entering from duct 18^a.

The operation of the structure shown in Fig. 2 is similar to that shown in Fig. 1 with the exception that on the compression 105 stroke of the pistons, the air in chamber 6 will first be forced into chamber 16, from which a scavenging air charge is delivered to the combustion chamber through duct 18^a and port 19^a. It will be observed that port 19^a is shorter than the exhaust port 22, and so located that the gases of combustion will first be permitted to exhaust and then fresh air will be permitted to enter through port 19^a as the piston uncovers this port. The 110 pressure in chamber 16 of Fig. 2 will of course be lower than the pressure in chamber 16 of Fig. 1, but it will be sufficient for scavenging purposes. While the piston is moving on its compression stroke to close the 115 scavenging port 19^a and exhaust port 22, the valve 45 will be adjusted by the means hereinafter explained, to admit air from the compression or supercharging duct 37 and allow it to pass through ports 47 and 39 to the 120 combustion chamber, thus filling said chamber with air under a higher pressure.

To operate the valve 45 automatically in

- response to pressure variations incident to the above described operation, I connect the controlling cylinder 48 shown in Fig. 3, to the duct 18^a. When the motor is in operation and port 19^a closed, the pressure in this duct will be sufficient to actuate a piston 49 in cylinder 48 in opposition to a spring 50 located between said piston and the cylinder head 51. The motion of this piston is transmitted through connecting rod 52 and arm 53 to the valve spindle 46 of valve 45, thereby adjusting the valve to the position in which it is shown in Fig. 2. But as soon as port 19^a is uncovered by piston 2, the pressure in duct 18^a will drop, owing to the delivery of the scavenging charge to the combustion chamber. This will of course cause a drop in pressure in the valve controlling cylinder 48, whereupon spring 50 will push piston 49 backwardly, and this motion will be transmitted to rotate valve 45 to the position indicated by dotted lines in Fig. 2, uncovering port 39 and the inlet port 47 of the valve chamber through which air then enters from duct 37, whereupon the supercharge will be delivered to the combustion chamber. This position of the valve will, however, be momentary, for as soon as port 19^a is closed by the piston, the pressure in duct 18^a will be built up from reservoir 16, and piston 49 will then again be actuated against the tension of spring 50 to readjust valve 45 to the position shown in Fig. 2. The drop in pressure in duct 18^a when port 19^a is open, may be secured in two ways. The duct 18^a may be made so small that the pressure therein cannot be maintained from chamber 16, or if desired, the chamber 16 may be small, in which case the pressure in said chamber, as well as in the duct 18^a, will be materially reduced by the delivery of the scavenging charge. In the latter case, the building up of pressure sufficient to actuate piston 49 against the tension of spring 50, will of course be dependent upon the action of piston 5, as it moves on the compression stroke to refill chamber 16.
- Valve 45 may be substituted for check valve 20 in the structure shown in Fig. 1. In such case, however, its operation will depend upon changes in pressure in the combustion chamber 1, and not upon changes in pressure in the duct 18. The cylinder 48 will therefore be connected with a port 60', which will be plugged when not thus in use. When cylinder 48 is so connected and used to operate the valve 45 in the structure shown in Fig. 1, it is obvious that said valve 45 may be closed at all times excepting during the interval when the pressure in the combustion chamber is reduced by the opening of the exhaust port 22, at which time the valve 45 will move to open position and remain open until the pressure in the combustion chamber is sufficiently built up on the compression stroke to actuate piston 49 in opposition to spring 50.
- Modified structure of Fig. 4.*
- Fig. 4 shows a substitute for the valve mechanism illustrated in Fig. 3. Differential pistons 60 and 61 are connected to operate in the cylinders 62 and 63, which are also connected, end to end, as shown. Cylinder 63 may be connected at 64 with the scavenging air duct 18^a of Fig. 2, and cylinder 62 may be connected with the supercharging duct 37. The pistons are so proportioned in area that the lower pressure of the scavenging air upon the larger piston will more than balance the higher pressure of the supercharging air upon the smaller piston-area of piston 61. These pistons operate also as slide valves controlling ports 65, 66, 67, 68 and 69 respectively, the pistons being suitably ported at 70 and 71.
- In this construction the ports 65 and 66 may lead to the combustion chamber and deliver air thereto for scavenging purposes, these ports performing the function of the port 19^a in Fig. 2 or may lead through the port 19^a to the combustion chamber if desired. The ports 67, 68 and 69 may correspond in function with the supercharging port 39 in Fig. 2.
- In the operation of the piston valve, it will be understood that when the valve is in the position shown in Fig. 4, it will be subject to the full pressure of the scavenging air and the supercharging air and will tend to remain in such position. But when the piston 2 uncovers the scavenging port 19^a (or ports 65 and 66), the pressure will be relieved upon piston 61, whereupon the pressure of the supercharging air upon piston 60 will move the pistons to the right, closing ports 65 and 66 and opening ports 67, 68 and 69. The piston valves will remain in this position until the pressure of the scavenging air upon piston 61 is again built up, whereupon the piston valves will return to the position indicated in Fig. 4.
- Where air is to be pumped for purposes other than motor operation, the relative size of piston 5 may be varied in accordance with the requirements. By increasing the diameter of air chamber 6 and compressor piston 5 beyond the requirements of the motor for scavenging and cylinder filling purposes, the device is converted into a combined motor and air compressor adapted to supply air for commercial purposes.
- I claim,—
1. A two cycle internal combustion motor provided with a combustion chamber, having inlet and exhaust ports adapted to be uncovered by the piston during its outward movement, a driving piston in said chamber,

- 1 a compressing chamber, a fluid compressing piston therein connected to move in synchronism with the driving piston, a reservoir adapted to receive fluid from the compression chamber, a valve adapted to prevent return of such fluid to the compression chamber, a duct leading from said reservoir to the combustion chamber, and communicating therewith during, and subsequently to the period of delivery through the exhaust port, a valve controlling the delivery of fluid from said duct to the combustion chamber, and fluid controlled means for automatically actuating said valve in one direction as pressure in the duct increases, together with means for automatically reversing the position of said valve when relieved from fluid pressure control.
2. A two cycle internal combustion motor provided with a combustion chamber, having inlet and exhaust ports adapted to be uncovered by the piston during its outward movement, a driving piston in said chamber, a compressing chamber, a fluid compressing piston therein connected to move in synchronism with the driving piston, a reservoir adapted to receive fluid from the compression chamber, a valve adapted to prevent return of such fluid to the compression chamber, a duct leading from said reservoir to the combustion chamber, and communicating therewith during, and subsequently to the period of delivery through the exhaust port, a valve controlling the delivery of fluid from said duct to the combustion chamber, and fluid controlled means for automatically actuating said valve in one direction as pressure in the duct increases, said compressing piston having a greater area of compressing surface than the driving piston.
3. A two cycle internal combustion motor provided with a combustion chamber, having inlet and exhaust ports adapted to be uncovered by the piston during its outward movement, a driving piston in said chamber, a compressing chamber, a fluid compressing piston therein connected to move in synchronism with the driving piston, a reservoir adapted to receive fluid from the compression chamber, a valve adapted to prevent return of such fluid to the compression chamber, a duct leading from said reservoir to the combustion chamber, and communicating therewith during, and subsequently to the period of delivery through the exhaust port, a valve controlling the delivery of fluid from said duct to the combustion chamber, and fluid controlled means for automatically actuating said valve in one direction as pressure in the duct increases, together with an auxiliary reservoir adapted to receive a portion of the compressed fluid.
4. An internal combustion motor comprising the combination of combustion and com-

pression chambers provided respectively with motor and compression pistons, said compression chamber being provided with outlet passages, one communicating with the combustion chamber in the annular zone of the exhaust port, and the other with said chamber between the first mentioned port and the cylinder head, and a valve adapted to open said ports successively.

5. An internal combustion motor comprising the combination of combustion and compression chambers provided respectively with motor and compression pistons, said compression chamber being provided with a plurality of outlets, one leading to the combustion chamber in the annular zone of the exhaust port, and the other to said chamber between the first mentioned outlet and the cylinder head, said outlets including suitable storage chambers for air under pressure and valve mechanism controlling delivery therefrom to the combustion chamber, together with separate means for delivering hydro-carbon to the combustion chamber.

6. An internal combustion motor comprising the combination of combustion and compression chambers provided respectively with motor and compression pistons, said compression chamber being provided with a plurality of outlets, one leading to the combustion chamber in the annular zone of the exhaust port, and the other to said chamber between the first mentioned outlet and the cylinder head, in combination with valve mechanism controlling delivery through said outlets to the combustion chamber, and separate means for delivering a combustible fluid thereto.

7. An internal combustion motor comprising the combination of combustion and compression chambers provided respectively with motor and compression pistons, said compression chamber being provided with a plurality of outlets, one leading to the combustion chamber in the annular zone of the exhaust port, and the other to said chamber between the first mentioned outlet and the cylinder head, in combination with valve mechanism controlling delivery through said outlets to the combustion chamber, an auxiliary reservoir, valve mechanism controlling diversion of compressed air from one of the outlet passages to said reservoir, and separate means for delivering combustible fluid thereto.

8. An internal combustion motor comprising the combination of combustion and compression chambers provided respectively with motor and compression pistons, said compression chamber being provided with a plurality of outlets, one leading to the combustion chamber in the annular zone of the exhaust port, and the other to said cham-

ber between the first mentioned outlet and the cylinder head, both of said outlets being independent of fuel delivery, in combination with valve mechanism controlling delivery through said outlets to the combustion chamber, a reservoir interposed between one of said outlets and the combustion chamber, and an auxiliary reservoir into which air

from the other compression chamber outlet may be diverted. 10

In testimony whereof I affix my signature in the presence of two witnesses.
